Application February 27, 1946, Serial No. 650,578

3 Claims. (Cl. 12—33)

1

The invention relates to novel and improved apparatus for adhesively attaching shoe soles to uppers, or for performing operations of like character.

As is known to those skilled in the art, one of the methods for attaching soles to uppers consists in applying an adhesive to the lower inturned portion of said uppers and/or to suitable upper surface portions of a sole, placing sole and upper in contact in proper relative position to each other, while the upper is preferably supported on a last, and maintaining sole and upper in tight contact, preferably with suitable heat application, until the adhesive acquires a permanent set.

The specific type of adhesive, and the precise details of present or prior methods, will not be here described with detailed accuracy, since such description is unnecessary for a comprehension of the present invention, which is mainly concerned with novel and improved apparatus, and with the novel steps of operation of the same.

An object of the present invention is to provide novel and improved apparatus and means for rigidly supporting the shoe upper and last, in combination with means for applying pressure of hydrostatic type to the sole to thereby produce an evenly distributed and homogeneous pressure to the contacting portions of the sole and the upper.

Another object of the invention is to provide novel and improved means whereby the operation mentioned in the last preceding paragraph is performed entirely by fluid pressure from any suitable source, without recourse to laborious and time consuming operations, either manual or mechanical.

Another object of the invention is to provide apparatus of the nature described which is simple, sturdy, easy to operate, and to assemble and disassemble, and otherwise to perform the various operations later to be described.

Other objects and advantages will be apparent from a study of the following specification in conjunction with the attached drawings, in which:

Fig. 1 is a view in side elevation of an apparatus embodying the present invention; Fig. 2 is a top plan view of the apparatus shown in Fig. 1; Fig. 3 is a sectional view taken on the line 3—3 of Fig. 2; Fig. 4 is a view in end elevation as seen from the left of Figs. 1 and 2; Fig. 5 is a sectional view taken on the line 5—5 of Fig. 1; Fig. 6 is a sectional view taken on the line 6—6 of Fig. 5, and showing the operating arm in side

10 elevation; Fig. 7 is a fragmentary sectional view similar in some respects to Fig. 6, but showing the several operating parts in operating relationship to a shoe; Fig. 8 is a schematic view showing the routing of the fluid pressure system; Figs. 9 and 10 are fragmentary sectional views, similar in many respects to Fig. 7 but showing adaptation of the apparatus to other types of shoe; Fig. 11 is a fragmentary perspective view of the front end of the apparatus.

15 Before the present invention here illustrated is described in detail, it is to be understood that the invention here involved is not limited to the details of construction or the specific arrangement of parts herein illustrated or described as the invention obviously may take various forms. It also is to be understood that the phraseology or terminology herein employed is for the purpose of description and not of limitation, the scope of the present invention being defined in the appended claims.

20 Speaking first generally, the novel apparatus herein to be disclosed consists of means for rigidly but adjustably holding the shoe parts in a suitably predetermined position, in operating conjunction with novel means for supplying the fluid pressure to maintain the sole and upper in contact while the adhesive is setting. The several parts will be described in the order indicated.

25 Referring now to the drawings, the apparatus comprises a box-like tank 10 having a main chamber or working chamber 11 (Figs. 3 and 5) said working chamber being laterally jacketed by two smaller fluid preheating chambers 12 and 13 from which the main chamber is separated, respectively, by walls 14 and 15. The apparatus may be supported on a floor or bench by legs 16. The open tops of jacket chambers 12 and 13 are 30 closed by a single U-shaped plate 17 (Figs. 2 and 3) which may be secured in any removable fashion to a horseshoe flange 18 extending around a substantial portion of the periphery of the tank assembly.

35 40 45 The inner front wall 19 (Figs. 5 and 6) of the main chamber is somewhat inclined to the vertical to leave an inward recess in the front end, the vertical periphery of which is adapted to receive a U-shaped cover plate 20 for a purpose 50 to be immediately described.

The open upper surface of all three chambers, and the front end recess outside wall 19, are closed by an elastic or flexible diaphragm 25 (Figs. 2 and 4) of rubber or other suitable material which completely covers the top of the

chambers, extending outwardly and being secured at the top between plate 17 and flange 18. The diaphragm extends continuously outwardly and downwardly over the front recess, being peripherally secured at the front end under plate 20. It will be apparent that when the diaphragm 25, and the securing plates 17 and 20 are fixed in place, as by cap screws or bolts 26, the main chamber 11 and the jackets 12 and 13 are individually sealed against fluid leakage, the diaphragm 25 over the main chamber 11 being yieldable in either direction responsive to pressure differential between the interior and exterior surfaces thereof.

As will be apparent the main chamber 11, through diaphragm 25, serves to supply fluid pressure to the shoe sole (Fig. 7), and the jacket chambers 12 and 13 serve to preheat the fluid to the proper operating temperature, after which the preheated fluid can be transferred, by means now to be described, to the main chamber at the proper time in the operating cycle.

The fluid circulating system will be described with reference to water as the medium of pressure, although it will be obvious to anyone skilled in the art that oil, or other suitable liquid or gaseous medium, could be adapted to the purpose.

Referring principally to the schematic showing in Fig. 8, water is admitted from the main, or other source of pressure, through conduit 30 to to four-way valve V, and thence, in the valve position shown in Fig. 8, through a conduit 31 carrying a reducing valve R and a pressure gauge G to two branch conduits 32 and 33 which enter, respectively, the preheating chambers 13 and 12; where the water is heated by an electrical heater H under the control of a thermostat T. This operation is conventional, and the apparatus is not shown in detail, the arrangement being easily understood and installed by a mechanic.

From the preheating chambers 12 and 13 the water, at a suitable point in the cycle is admitted to the main chamber 11 through conduits 34, 35, and 36, which latter enters the bottom of chamber 11 (Fig. 3). Discharge from said main chamber at an appropriate point in the cycle is provided for through outlet conduits 37, 38, and 39 to the valve V and thence to a sewer or other disposition through conduit 40 when valve V is appropriately operated.

The arrangement just described is not critical, and changes of piping may be made to suit particular requirements. For example, although two preheating chambers in a jacketed assembly, as here shown, forms a balanced arrangement which maintains temperature equilibrium with very satisfactory thermal uniformity and economy, it is quite likely that a successful operation can be effected with one preheating chamber, which may, if convenient or desirable, be physically removed to a location remote from the chamber 11.

Apparatus for holding the shoe upper and sole in adhesive contact will now be described.

The shoe is retained in a fixed position by an operating arm a portion of which normally overhangs the top surface of the main chamber. Said arm 41 is L-shaped in contour, having a horizontal component 42 which overhangs as aforesaid and a vertical component 43 which, in conjunction with means fixed with respect to the tank, fixes the arm in operating position after it has been placed in proper operating adjustment.

Adjacent its rear wall the tank is provided with a vertical runway or channel which, in the em-

bodiment here shown, is defined between two upright posts 45 and 46, here shown as integral with the rear end of the tank. The upper ends of the posts extend substantially above the plane 5 of the top clamping plate 17. The parallel inner opposed wall faces 48 and 49 of the posts are provided with a pair of matched grooves 50 and 51 aligned in a vertical plane and extending upwardly from the lower ends of the posts to a level 10 near, but short of, the upper ends of the posts. The inner faces 48 and 49 of the posts, the said grooves 50 and 51, and the rear wall surface 52 of the tank define the channel, and form bearing surfaces for sliding travel of the vertical portion 15 43 of the arm during operation thereof, as will appear.

Arm 41 is generally T-shaped in cross section, being provided with a pair of laterally extending flanges 56. On the vertical component 43 of the 20 arm the flat inner face 57 of the arm (Fig. 6) has a sliding contact with a rear wall 52 of the channel, and the side edges of the flanges 56 have sliding contact with the inner faces 48 and 49 of posts 45 and 46. An enlarged boss 59 at the 25 lower end of arm portion 43 has two opposed projecting pins 60 and 61 which have a sliding key engagement with grooves 50 and 51 respectively.

It will now be apparent that arm 41 is vertically freely movable manually to an upper limit 30 wherein pins 60 and 61 reach the upper end of grooves 50 and 51. At such upper end the lower inner corner 65 (Fig. 1) of the vertical portion 43 of the arm clears the upper end of the wall 52 (Fig. 5) so that at such upper limit the arm 35 may then be pivotally swung outwardly to the broken line position of Fig. 1, which is an inactive or rest position. A projecting finger 66 on the lower end of the arm has then swung into surface abutment with an undercut inclined portion 67 of wall 52 (Fig. 1), and said abutting contact, in conjunction with the position of pins 60 and 61 in their respective grooves locks said arm in its rearwardly inclined rest position. Dropping of the arm is further prevented in such 45 rest position, since corner 65 has swung inwardly above the upper corner of wall 52 so that any downward movement of the arm is thus prevented as long as the arm position 43 is outwardly inclined from the vertical. The function and 50 significance of the various arm positions will become apparent in connection with the description of the operation of the device hereinbelow.

The horizontal portions 56a of lateral flange 56 serve as key tracks for a freely slidable rider 70 which is provided with suitable grooves 70a which ride on said tracks. Beneath said rider is a saddle 71 which is adapted to seat on the toe portion of the shoe upper (Fig. 7). As rider 70 is moved to the left (Figs. 1 and 6) it is removable from the left end of the flange 56a; and it is adjustable on said flange for any size of shoe merely by sliding movement to the right or left.

The extreme left end of the tip end 42a of arm portion 42, is slightly upwardly offset, and, provided with opposed key flanges 56b which cooperate with grooves 72 in a slidable rider 73, which has a depending portion 74, the function of which is to abut the upper surface of a last 82 (Fig. 7) when the soeling operation is being performed. It will be apparent that rider 73 may be withdrawn to the left (Figs. 1 and 6) and thus may be completely removed from the arm. It will be further apparent that rider 73 may be adjusted laterally to accommodate different sizes of shoes.

The operation of the device will now be described, with reference to the various drawings, and particularly to Figs. 1, 7, and 8. Starting at a point in the cycle at which main chamber 11 contains sufficient heated water to maintain diaphragm 25 in approximately horizontal position, as indicated in Fig. 6, a shoe sole 80 is placed on the diaphragm, and a shoe upper 81, encasing a last 82, is coated at suitable locations with an adhesive, and disposed on the sole at the proper position to be permanently united thereto. During this operation the arm 41 is swung to the rest position shown in broken line in Fig. 1. After the shoe and sole are disposed as aforesaid, the arm is swung to the operating position of Fig. 7, wherein the saddle 71 rests on the shoe toe, and the rider 73 abuts the top of the last. For accurate registry the operating position of rider 73 may be vertically adjustable by means of a vertically threaded extension 83 and an adjusting nut 84, said extension passing upwardly through a vertical slot 85 in arm tip 42a.

Arm 41 being moved downwardly until operating contact is reached as aforesaid, pins 60 and 61 are correspondingly moved downwardly from the top of their grooves 50 and 51 to the intermediate position indicated in Fig. 7. Attention is here called to the fact that in this or other intermediate positions of pins in grooves, upward pressure against arm portions 42 or 42a will have a tendency to attempt to swing the arm 41 on the pivot pins 60 and 61, but such swinging movement of the arm is rendered impossible by reason of the fact that a portion of the face 57 of the vertical portion of the arm has planar contact with wall 52 of the operating channel, so that arm portion 43 can only depart from the vertical when the lower corner 65 passes above wall 52 as shown in Fig. 1, in the broken line position. Further, arm 41 can be moved vertically only if the moving force is applied in such manner as to be effective directly below or above the pivot pins 60 and 61. Any force applied out of vertical alignment with said pins is wasted in attempts to tilt the arm as aforesaid. It is accordingly apparent that as long as there is substantial planar contact between the face 52 and wall 57 upward pressure beneath and against riders 70 and 73 is resisted as effectively as if arm 41 were integrally fixed with respect to the tank assembly.

The shoe upper being thus braced against upward movement by arm 41, valve V is turned to the position shown in Fig. 8, permitting pressure fluid from the main 30 to proceed through conduits 31, 32, and 33, to the preheating chambers 12 and 13, and thence through conduits 34, 35, and 36, to the operating chamber 11. A certain amount of freshly preheated water, at a temperature for example between 75° F. and 90° F., enters chamber 11 and applies a hydrostatic force upwardly against sole 80 through the medium of diaphragm 25. Being hydrostatic in nature, the force is evenly applied to the whole lower surface of sole 80, and may thus be maintained for any desired period.

At the end of the required cementing period, valve V is turned to establish discharge communication between conduits 39 and 40. The weight 70 of the shoe and last assembly is transmitted downwardly through diaphragm 25 and ejects a certain amount of water through the discharge conduits 37, 38, 39 and 40, until the diaphragm has collapsed to its lowermost position, after which 75

further discharge tends to develop an incipient vacuum within chamber 11, and thus terminates or greatly reduces water discharge. The valve V is then turned to an intermediate fully closed position, permitting no flow in either direction. When the pressure is released, the arm 41 is raised manually to its topmost position and then swung to the rest position so as to permit substitution of another shoe. The shoe is then removed and replaced by another, after which valve V is again turned to the position of Fig. 8, such operation injecting a fractional increment of preheated water from chambers 12 and 13 to chamber 11 so as to apply pressure for the next operation.

If desired the arm 41 may be entirely removed from the apparatus by first sliding riders 70 and 73 to the left to remove them from their respective key flanges 56a and 56b. After such removal the arm may be lowered without tilting it, until pins 60 and 61 emerge from the bottom ends of grooves 50 and 51, after which the arm can be withdrawn rearwardly from its channel.

The shoe illustrated in Fig. 7 is of relatively small size, and of the type wherein the heel, sole and arch do not vary materially from a common plane. Fig. 9 illustrates a convenient arrangement for a man's shoe 90, representing the largest shoe to be accommodated by the apparatus. In such instance the heel portion of the shoe may extend within the top front clearance space (Fig. 11) defined by the open ends of the U-shaped horizontal cover plate 17, and the U-shaped vertical clamping plate 29, the heel 30 itself being above the inclined inner front end wall 19. The diaphragm 25 of course retains the upward and outward thrust of the water.

Fig. 10 illustrates a convenient arrangement for a high heeled shoe. The heel 91 may extend downwardly outside wall 19, and may even incline inwardly under pressure, such inward inclination being unhindered by reason of the inward inclination of front wall 19, which expedient prevents breaking or distortion of the heel or sole.

As best seen in Fig. 11, the open front corner permits support of the heel end of large shoes, such support being taken care of by the diaphragm 25 alone.

It will be apparent to those skilled in the art that by means of the apparatus described, a proper thermal balance can be obtained at any temperature desired. The size of the preheating chambers relative to the size of the main chamber can be controlled so that when the predetermined increment of preheated water arrives in the main chamber it will restore the proper initial temperature for the start of the cementing operation. This can be additionally controlled by the capacity of heaters H (Fig. 8) and the thermostats T. Although the apparatus will work satisfactorily as just described without automatic or manual air venting, suitable air vents, check valves, etc., may be provided if desired. The reducing valve T and the gauge G are provided to properly accommodate and control the fluid pressure to the valve suited to the process.

One of the advantageous features of the apparatus just described is that the operating arm is effectively and automatically locked in any operating position throughout a vertical height coextensive with normal variations in shoe size and last heights. The arm will fixedly maintain its preset height relative to the tank assembly and shoe. This is achieved solely by properly deter-

mining the control and arrangement of the relatively sliding parts of the arm in the channel with respect to the pivot line of the arm. Said arm is also locked in its rest position so as to be incapable of slipping therefrom and injuring the apparatus or the operator. Unlike previous available apparatus no mechanical pressure is required such as is developed through levers, hand wheels, cams, etc., since the only manual operation is the lowering of the arm from its rest position to its operating position and the opening of the pressure valve.

While we have shown and described only one unit for operating on one shoe, it is obvious that a twin assembly will ordinarily be made up to work simultaneously on both members of a pair of shoes. This can be done in any desired manner, and the fluid pressure system can be set up in duplicate under the control of two respective valves, so that cyclic operations on individual shoes may be chronologically staggered for convenient operation by a single operator if desired.

What we claim is:

1. Apparatus for adhesively permanently uniting a shoe sole to an upper comprising a box-like tank having rigid side, end, and bottom walls; said tank having two longitudinal partitions therewithin and extending from a front to a rear wall whereby to divide said tank into three compartments consisting of a central working chamber and two preheating chambers spaced one on each side of said working chamber, means for conveying fluid to said preheating chambers, means for heating said fluid, means for controlling the temperature of said fluid, and means for transferring said fluid under pressure to said working chamber, top wall means for all three said chambers, the top wall for said working chamber consisting of an impervious diaphragm of flexible material yieldably responsive to pressure differentials within and without said working chamber; said diaphragm being adapted to support thereon an adhesively joined shoe sole and upper, an operating arm having a horizontal portion adapted to overhang said upper wall, and a vertical portion extending partially downward behind said tank and having adjustably sliding contact with the rear wall of said tank, said horizontal portion of said arm carrying depending means for maintaining said shoe upper and sole in operative contact with said diaphragm, and means for applying hydrostatic pressure from said working chamber through said diaphragm to said shoe sole.

2. Apparatus for adhesively permanently uniting a shoe sole to an upper comprising a box-like tank having rigid side, end, and bottom walls, said tank having two longitudinal partitions therewithin and extending from a front to a rear wall whereby to divide said tank into three compartments consisting of a central working chamber and two preheating chambers spaced one on each side of said working chamber, means for conveying fluid to said preheating chambers, means for heating said fluid, means for controlling the temperature of said fluid, and means for transferring said fluid under pressure to said working chamber, top wall means for all three said chambers, the top wall for said working chamber consisting of an impervious diaphragm of flexible material yieldably responsive to pressure differentials within and without said working chamber, said diaphragm being adapted to support thereon an adhesively joined shoe sole and upper, an operating arm having a horizon-

tal portion adapted to overhang said upper wall, and a vertical portion extending partially downward behind said tank and having adjustably sliding contact with the rear wall of said tank;

5 said horizontal portion of said arm carrying depending means for maintaining said shoe upper and sole in operative contact with said diaphragm, and means for applying hydrostatic pressure from said working chamber through

10 said diaphragm to said shoe sole, the front end wall of said chamber having an opening therein, and said diaphragm having a forward and downward extension extending over said opening to cover and seal said opening, whereby the heel portion of a shoe supported on said diaphragm as aforesaid may extend forwardly and downwardly beyond the front wall of the tank, while permitting said downward extension to resiliently accommodate itself thereto.

15 3. Apparatus for adhesively permanently uniting a shoe sole to an upper comprising a box-like tank having rigid side, end, and bottom walls; said tank having two longitudinal partitions therewithin and extending from a front to a rear wall whereby to divide said tank into three compartments consisting of a central working chamber and two preheating chambers spaced one on each side of said working chamber, means for conveying fluid to said preheating chambers,

20 means for heating said fluid, means for controlling the temperature of said fluid, and means for transferring said fluid under pressure to said working chamber, top wall means for all three said chambers, the top wall for said working chamber consisting of an impervious diaphragm of flexible material yieldingly responsive to pressure differentials within and without said working chamber, said diaphragm being adapted to support thereon an adhesively joined shoe sole and upper, an operating arm having a horizontal portion adapted to overhang said upper wall, and a vertical portion extending partially downward behind said tank, said horizontal portion of said arm carrying depending means for maintaining said shoe upper and sole in operative contact with said diaphragm, and means for applying hydrostatic pressure from said working chamber through said diaphragm to said shoe sole, the front end wall of said chamber having an opening therein, and said diaphragm having a forward and downward extension extending over said opening to cover and seal said opening, whereby the heel portion of a shoe supported on said diaphragm as aforesaid may extend forwardly and downwardly beyond the front wall of the tank, while permitting said downward extension to resiliently accommodate itself thereto.
